UNITED STATES PATENT OFFICE.

JERRY KUBELKA, OF RIDGEWOOD, NEW YORK.

WEATHERPROOF CONCEALED HINGE AND JAMB CONSTRUCTION.

Application filed December 19, 1927. Serial No. 241,116.

This invention relates to a closure hinge and jamb construction.

Some of the objects of the present invention are: to provide a hinge construction for closures, such as casement windows and doors, which will be concealed, and which will be protected from the elements of weather; to provide a construction for closures of the indicated character which will exclude dust and dirt from between the moving parts; and to provide a novel jamb construction for metal casements or frames and their connected closures.

The nature of the invention and its distinguishing features and advantages will appear when the following specification is read in connection with the accompanying drawings, in which—

Figure 1 is a fragmentary side elevation of a casement and window embodying the features of the present invention.

Fig. 2 is a sectional view on an enlarged scale taken on the line 2—2 of Fig. 1.

Fig. 3 is a view similar to Fig. 2 showing the closure open.

Fig. 4 is a sectional view taken on the line 4—4 of Fig. 3.

Fig. 5 is a sectional view taken on the line 5—5 of Fig. 3.

Fig. 6 is a collective view of the hinge parts which are shown in perspective.

Fig. 7 is a sectional view on an enlarged scale taken on the line 7—7 of Fig. 1.

Fig. 8 is an enlarged sectional view taken on the line 8—8 of Fig. 1.

The present invention contemplates the provision of a weatherproof concealed hinge construction for closures such as high class metal casement windows and doors, and other structural features which serve their purpose without detracting from the appearance of the windows or doors.

Referring now more particularly to the drawings, it will be apparent that, there has been shown a casement or frame 10 of metal. The said casement or frame 10 will be of rectangular construction. The said casement or frame 10 has associated therewith a closure 11 which constitutes the closure of a window in the present instance. The said closure 11 is hingedly connected with the casement or frame 10 in the manner and by the means presently to be described. The casement or frame 10 includes a stile 12 which has formed thereon a cross sectionally semi-circular channel 13 which provides a verti-

cal groove 14. The said channel 13 is disposed within the plane of the casement or frame 10. The closure 11 includes a metal frame 15 having formed thereon an angular channel 16 within the plane of the frame 15. Two or more hinge joints are provided according to the size and weight of the closure 11, and these joints will be identical, and therefore a description of one will suffice for all. The hinge joint is formed by the use of a hinge block 17 fastened in the present instance to the channel 13 of the casement 10 by suitable fastening elements such as the screws 18. The block 17 is of a shape to fit in or conform to the semi-circular wall of the channel 13, and has an angular member 19 which receives one edge of the channel 13 to facilitate the assemblage of the block and to keep it properly located. The block 17 has a vertical bore 20. Hinge brackets 21 of angular construction are provided, and each bracket 21 has a pintle 22. The brackets 21 and pintles 22 are arranged in pairs, one pair to each block 17. The brackets 21 and pintles 22 are arranged respectively above and below the related block 17 and are attached to the channel 16 of the closure 11, by the use of suitable fastening elements such as the screws 23. The pintles 22 are disposed in the bore 20 of the block 17. The channel 16 on the frame 15 is cut out as at 24 to accommodate the block 17 and to allow the closure 11 to be swung to opened and closed positions.

It is to be understood that each block 17 of the hinge joint may be integral with the closure 11, and that the pintle brackets 21 of each hinge joint may be secured to the channel 13.

In accordance with another feature of the invention the channel 16 has a vertical angular extension which presents cleaning edges 25 movable within the channel 13 on the casement or frame 10. The said edges 25 serve for the purpose of excluding any dust, dirt or other foreign matter from entering the channel 13. It will be apparent that the said edges 25 are movable in response to the movement of the closure 11.

In accordance with another feature of the present invention there is provided a jamb construction which occurs around the top and bottom of the casement or frame 10 and the stile opposite that with which the closure 11 is hingedly connected. The said jamb construction consists of an angular channel 26 on the casement or frame 10,

- and an angular channel 27 on the closure 11. The said channels 26 and 27 respectively have portions 28 and 29 which overlap each other when the closure 11 is in a closed position, as shown most clearly in Figs. 7 and 8. It will be apparent that the portions 28 and 29 overlap vertically and therefore eliminate any friction. It is also to be understood that the lower corner of the frame 15 at the hinge side, rests on the lower rail of the casement or frame 10, thereby sharing the weight of the closure with the means which hingedly connects the closure 11 with the casement or frame 10.
- 15 From the foregoing it will be apparent that there has been described a hinged construction which will be concealed and which will therefore be protected from the elements of weather; that means is provided for excluding dust and dirt or other foreign matter from between the moving parts; and that the construction presents features which properly distribute the weight of the closure to reduce friction to the minimum.
- 20
- 25 I claim:
1. A casement and closure hinge construction, comprising pintles fastened to the closure, and a part fastened to the casement in which the pintles turn, the pintles being enclosed by portions respectively on the casement and closure.
  2. A closure construction characterized by a stile having a vertical groove, a closure, said closure being hingedly connected with said stile by concealed hinge means, said closure having vertical edges which move in said groove in response to movement of the clo-

sure to keep the groove cleaned of foreign matter.

3. A casement and closure hinge construction, comprising a block fastened to the casement, pintles respectively fastened to the closure above and below the block with the pintles turnable in the block.

4. A closure construction, comprising a frame having a vertical cross-sectional semi-circular channel disposed within the plane of said frame, a closure, hinge blocks fastened to the semicircular channel in the groove presented thereby, an angular channel on said closure within the plane of said closure, and angular hinge brackets fitting within and fastened to said angular channel and respectively positioned above and below each hinge block, each bracket having a pin-
50
55
55
tle turnable in its related block.

5. A closure jamb construction, comprising a metal jamb in the form of an angular channel, and a metal closure frame having an angular channel within the plane of the frame, portions of the frame channel respectively overlapping portions on the jamb channel when the frame is closed upon the jamb.

6. A casement construction characterized by a stile having a channel; a closure having a channel; brackets each having a pintle; means fastening each bracket to the channel on the closure, a block, and means fastening the block to the channel on the stile, said pintles being turnable in a bore in said block.
